UNITED STATES PATENT OFFICE.

GEORGE E. BABCOCK, OF FORT PLAIN, NEW YORK.

FRONT RUNNING-GEAR.

No. 877,159.

Specification of Letters Patent.

Patented Jan. 21, 1908.

Application filed September 4, 1907. Serial No. 391,364.

To all whom it may concern:

Be it known that I, GEORGE E. BABCOCK, a citizen of the United States, residing at Fort Plain, in the county of Montgomery 5 and State of New York, have invented certain new and useful Improvements in Front Running-Gears; and I do declare the following to be a full, clear, and exact description of the invention, such as will enable others skilled in the art to which it appertains to 10 make and use the same.

This invention relates to improvements in front running gears for children's wagons.

The object of the invention is to provide 15 an improved fifth wheel and tongue connection for the front axle of a wagon, and improved means for fastening the wheels on the axle.

With these objects in view, the invention 20 consists of certain novel features of construction, combination and arrangement of parts as will be more fully described and particularly pointed out in the appended claims.

25 In the accompanying drawings, Figure 1 is a perspective view of the front running gear of a toy wagon constructed and arranged in accordance with the invention; Fig. 2 is a vertical sectional view taken on 30 a line with the axle; Fig. 3 is a central vertical sectional view taken at right-angles to Fig. 2; Fig. 4 is a detail perspective view of the tongue connection; Fig. 5 is a similar view of the fifth wheel plate; Fig. 6 is a 35 similar view of the tripod-shaped connecting bars; Fig. 7 is a detail cross sectional view of the axle, showing the manner of securing the ends of the bolster thereto and Fig. 8 is a detail perspective view of one of the 40 wheel-retaining devices.

Referring more particularly to the drawings, 1 denotes the front axle of a toy or child's wagon. On the axle, midway between its ends, is arranged a tongue connection, 2, which is here shown and is preferably formed of heavy sheet metal bent in substantially U-shape to provide a pair of forwardly projecting plates, 3, between which the inner end of the tongue is pivotally 45 connected. The looped end of the connection is provided with a downwardly projecting extension through which and adjacent to the lower edge thereof, are formed alined apertures, 4, through which the axle, 1, extends. In the upper edge of the connection, immediately above the aperture 4,

are formed oppositely disposed rectangular notches or recesses, 5, in which is adapted to be seated a transversely disposed bolster, 6, which is in the form of a flat metal bar 60 having a centrally disposed, downwardly bent portion, 7, which is disposed between the sides of the U-shaped tongue connection and serves to prevent any lateral movement of the latter. 65

The bolster is bent downwardly at its opposite ends to form axle engaging lugs, 8, in which are formed apertures, 9, through which the axle extends. In the axle 1, at the point where the same is engaged by the 70 lugs, 8, of the bolster, are formed oppositely disposed, vertical notches, 10, into which the edges of the apertures 9 in the lugs, 8, are adapted to be upset or clenched by denting in the outer edges of the lugs, 8, as shown. 75 By thus connecting the axle with the bolster, the former is rigidly held against rotation or lateral movement.

Arranged in the upper portion of the tongue connection is a fifth wheel plate, 80 12, said plate having its opposite ends bent downwardly on each side of the bolster and said plate engages and rests on the bolster in the downwardly bent central portion, 7, thereof, thus providing an interlocking connection between said plate, the bolster and the tongue connection. The forward downwardly bent end of the plate, 12, is provided on each side with laterally projecting lugs, 85 13, which are adapted to be engaged with oppositely disposed rectangular apertures, 14, formed in the tongue engaging plates, 3, adjacent to their upper edges. The downwardly bent rear end of the plate, 12, is provided with a rearwardly projecting lug, 15, 90 95 which is adapted to be engaged with an elongated opening, or slot, 16, formed in the looped end of the tongue connection.

Pivots connected to the fifth wheel plate by means of a bolt, rivet or other suitable connection, 17, are tripod-shaped body connecting bars, 18, the upper ends of which are bent in a horizontal plane to provide attaching lugs, 19, in which are formed bolt holes, 20, to receive fastening bolts, by 100 means of which said bars are connected to the body of the wagon. By thus pivotally connecting the bars 18 to the fifth wheel plate, said plate, together with the tongue connections, bolster and axle, may be turned 105 110 freely in any direction to guide the wagon.

In the sides of the axle, adjacent to its

ends, are formed opposite, transversely disposed notches or recesses, 21, with which are adapted to be engaged wheel-retaining disks 22, said disks having formed therein rectangular notches or recesses, 23, said notches forming oppositely disposed wings 24 in the disk 22, which engage the notches 21 in the opposite sides of the axle, and thus support the disks 22 in position to hold the wheel in place on the ends of the axle. The disks 22 are held against casual disengagement from the notches 21 by upsetting or bending the lower ends of the wings, 24, laterally in opposite directions.

15 Having thus fully described my invention, what I claim as new and desire to secure by Letters-Patent, is:

1. In a front running gear of the character described, the combination with the front axle, of a substantially U-shaped tongue connection arranged thereon, tongue receiving plates formed on the forward end of said connection, a bolster bar having a centrally disposed downwardly projecting portion adapted to engage the upper edges of the tongue connection, downwardly bent apertured axle engaging lugs formed on the outer end of said bolster bar, means to rigidly connect said lugs with the axle, a fifth wheel plate arranged in the upper edge of said tongue connection, attaching lugs formed on the opposite ends of said fifth wheel plate and adapted to engage apertures or slots formed in the tongue connection, and means to pivotally connect said fifth wheel plate with the body of the wagon, substantially as described.
2. In a front running gear of the character described, the combination with an axle having formed therein vertically disposed parallel notches, a substantially U-shaped tongue connection having formed therein oppositely disposed axle engaging holes through which said axle extends and having in its upper edges oppositely disposed rectangular notches, a bolster comprising a flat metal bar bent midway between its ends to form a depressed portion adapted to be engaged with the rectangular notches in the upper edges of said tongue connection, downwardly projecting apertured lugs formed on the opposite ends of said bolster, said lugs being adapted to engage the parallel notches in the opposite sides of the axle and to be upset or clenched therein, a fifth wheel plate having downwardly bent opposite ends, attaching lugs formed on said ends and adapted to be engaged with said tongue connection, and means to pivotally connect said fifth wheel plate with the body of the wagon, substantially as described.
3. In a front running gear of the character described, the combination with an axle having formed therein vertically disposed parallel notches, a substantially U-shaped tongue

connection having formed therein oppositely disposed axle engaging holes through which said axle extends and having in its upper edges oppositely disposed rectangular notches, a bolster comprising a flat metal bar bent midway between its ends to form a depressed portion adapted to be engaged with the rectangular notches in the upper edges of said tongue connection, downwardly projecting apertured lugs formed on the opposite ends of said bolster, said lugs being adapted to engage the parallel notches in the opposite sides of the axle and to be upset or clenched therein, a fifth wheel plate having downwardly bent opposite ends, attaching lugs formed on said ends and adapted to be secured in said tongue connection, tripod-shaped body connecting bars adapted to be secured to the underside of the wagon body, and a pivot bolt or rivet to pivotally connect the said tripod bars with the fifth wheel plate, substantially as described.

4. In a front running gear of the character described, the combination with the front axle, of a tongue connection arranged thereon, a bolster bar having a depressed central portion to form shoulders to engage said tongue connection, means to rigidly connect the opposite ends of said bolster with the axle, a fifth wheel plate arranged in said tongue connection over the engaging portion of said bolster, attaching lugs on said fifth wheel plate to engage said tongue connection whereby the latter and said plate are fastened together, and tripod-shaped body connecting bars, pivotally secured to said fifth wheel plate, substantially as described.

5. In a front running gear of the character described, the combination with an axle having formed in its opposite sides inner and outer pairs of parallel vertically disposed notches, of a tongue connection arranged on said axle, a bolster bar having a central depressed portion to form shoulders to engage said tongue connection, apertured lugs on the opposite ends of said bolster bar to engage the inner pair of notches in said axle, whereby the latter is held against rotation and lateral movement, a fifth wheel plate adapted to be secured in the upper portion of said tongue connection, tripod-shaped body connecting bars pivotally secured to said fifth wheel plate, and notched wheel-retaining disks adapted to be engaged with the outer pair of parallel notches in the ends of the axle and to be upset therein to prevent their casual removal, substantially as described.

In testimony whereof I have hereunto set my hand in presence of two subscribing witnesses.

GEORGE E. BABCOCK.
